[57] **CLAIM**

The ornamental design for a combination support and
control for a heat shrink roller, as shown and described.

DESCRIPTION

FIG. 1 is a front elevational view of a combination support and control for a heat shrink roller design of the present invention.

FIG. 2 is a bottom plan view thereof.

FIG. 3 is a top plan view thereof.

FIG. 4 is an elevational view thereof.

FIG. 5 is an elevational view thereof.

FIG. 6 is a rear elevational view thereof.

FIG. 7 is a perspective view thereof from the front.

FIG. 8 is a perspective view thereof from the rear.
